(57) **CLAIM**

The ornamental design for an electromyography (EMG) sensor, as shown and described.

DESCRIPTION

FIG. 1 is a top front perspective view of an electromyography (EMG) sensor showing my new design;

FIG. 2 is a bottom rear perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a top plan view thereof; and,

FIG. 8 is a bottom plan view thereof.
